UNITED STATES PATENT OFFICE.

GEORGE R. PAULUS, OF CANTON, OHIO, ASSIGNOR TO UNITED ELECTRIC COMPANY, OF CANTON, OHIO, A CORPORATION OF OHIO.

VACUUM CLEANER.

Application filed September 12, 1918. Serial No. 253,897.

To all whom it may concern:

Be it known that I, GEORGE R. PAULUS, a citizen of the United States, residing at Canton, in the county of Stark and State of Ohio, have invented certain new and useful Improvements in Vacuum Cleaners, of which the following is a specification.

The invention relates to vacuum cleaners and other like machines operated by electric power and manipulated by propeller handles having forked arms pivotally connected to the sides of the machines; and the object of the improvement is to provide means for automatically opening and closing the electric circuit by swinging the handle from a reclined propelling position to and from an upright non-propelling position, for normally holding the handle in upright non-propelling position, and for locking the handle in various positions.

Portable electric vacuum cleaners and like machines are usually operated by a handle pivotally connected by forked arms to the sides of the machine, and carrying a dust separating and collecting bag and a portion of the electric cord between the handle and the rear end of the machine.

When the machine is in use, the handle normally extends upward and rearward at about forty-five degrees so that its rear end can be conveniently grasped by the hand for propelling the machine to and fro upon a floor, during which operation it is desirable that the electric circuit shall be closed for a constant operation of the machine.

When, however, the machine is not in use, it is customary to lift the handle so that it will stand upright in non-propelling position upon the machine, and while in this position, the electric current should be opened so that the machine will not be running while idle.

When lifted into upright position, the handle should be held perpendicular to the plane of the machine so that its body will not swing upon the handle pivots when being carried by the handle; and it is also desirable to lock the handle in various positions for different kinds of work.

By the present invention, a cam switch plate is located at one side of the machine and a laterally yielding spring detent is provided on the adjacent handle arm for automatically operating the switch to open and close the circuit by a forward and rearward

swinging of the handle arm, and also for automatically co-ordinating these parts when the switch has been operated by means other than by the handle arm; and a stop and a spring arm are provided on the other side of the machine for normally engaging the other handle arm to hold the handle perpendicular to the plane of the body, and a spring latch is also located on said arm for locking the handle in various positions.

A preferred embodiment of the invention, as applied to a vacuum cleaner, is illustrated in the accompanying drawings, forming part hereof, in which—

Figure 1 is a side elevation of a portable electric vacuum cleaner showing the handle holding and locking devices;

Fig. 2, a fragmentary perspective view showing the switch plate and spring detent on the other side of the vacuum cleaner;

Fig. 3, a fragmentary vertical section showing the switch operating devices;

Fig. 4, a fragmentary side elevation showing the operation of the cam switch plate by the spring detent;

Fig. 5, a detached perspective view of the spring detent;

Fig. 6, a fragmentary view showing the operation of the switch controlling arm;

Fig. 7, a vertical section showing the handle holding and locking devices;

Fig. 8, a fragmentary side elevation of the same with the latch plate removed;

Fig. 9, a detached perspective view of the segmental rack;

Fig. 10, a detached perspective view of the spring arm; and

Fig. 11, a detached perspective view of the latch plate.

Similar numerals refer to similar parts throughout the drawings.

The handle 1 is provided with the forked arms 2 and 2^a, which are pivoted at 3 and 3^a to the opposite sides of the fan case 4 of the vacuum cleaner; and the segmental rack 5 is secured to one side of the fan case inside the arm 2 concentric with the pivot thereof.

The latch plate 6 is slidably mounted on the outer side of the arm 2 and is held for limited endwise movement by the shouldered rivets 7 secured to the arm, the shanks 8 of which extend through the slots 9 in the latch plate, and the heads 10 of which engage the outer side of said plate. The bearing ball 11 is

located in the aperture 12 in the handle arm 2 which permits the ball to protrude beyond the outer face of the arm for impinging the inner side of the latch plate; and the leaf 5 spring 13 is secured as by the rivet 14 at its upper end to the inner side of the handle arm and extends downward back of the ball so as to press it forward in its aperture against the spring latch. The parts are so 10 proportioned and arranged that the bearing ball will partially enter the upper end of the upper slot 9 in the latch plate when the same is moved to its upper limit so that the bearing ball holds the latch upward in 15 a more or less positive manner; and when the latch is moved downward, the bearing ball is pressed backward against the leaf spring 13 which serves to frictionally hold the latch in a given position.

20 The locking lug 15 is secured, as by the rivet 16, to the inner side of the latch plate 6 intermediate the guide slots 9 therein, and this lug protrudes through the longitudinal slot 17 provided in the handle arm 2, to engage with the notches 18 in the segmental rack 5 when the latch plate is moved downward upon the arm, but to ride freely over the upper edge 19 of the rack between the 25 slots when the latch plate is moved upward 30 upon the arm. The segmental plate is extended upward in front of the forward notch 18, and in rear of the rearward notch 18, to form positive stops 20 and 21 for the handle arm when the lug 15 is moved upward 35 thereon, for positively limiting the forward and rearward movements of the handle of the machine.

The spring arm 22 is secured to the inner 40 side of the segmental rack and extends upward in the path of the locking lug 15, immediately in front of the position of said lug when the handle is lifted upward to the positive stop 20, as shown in Fig. 1, and serves to hold the handle in this non-propelling position. The spring arm is inclined or bevelled 45 inwardly on each side 23 so as to present a cam face to the locking lug which is thus permitted to pass the arm by forcing it inward, when the handle is moved with the 50 sufficient power to overcome the strength of the spring.

The handle may be locked either in upright position as shown in Fig. 1 or in rearwardly inclined position as shown in 55 Fig. 2, or in a further reclined position, not shown, by pushing the latch plate downward until the locking lug enters one of the notches 18. In this position the latch lug is held by pressure of the bearing 60 ball 11, until the latch plate is moved upward with sufficient force to overcome such pressure; whereupon the latch plate is held upward to hold the lug free above the upper edge 19 of the segmental rack, by the partial 65 protrusion of the bearing ball in the upper

end of the upper slot 9 in the latch plate, so that the handle may be swung on its pivots.

The switch arm 24 and the controlling arm 25 are fixed on the pintle 26, which is journalled in the switch block 26^a in the 70 motor case, and the controlling arm is adapted to be swung between the stops 27 and 27^a from its forward position shown in full lines in Fig. 6, when the controlling arm 25 closes the circuit, to its rearward 75 position shown in broken lines in the same figure, when the switch arm opens the circuit.

The pendent U-shaped switch bracket 28 is pivoted by its inner arm to the same pintle 26 which carries the switch arm to which it is connected by the expansion spring 29, and the yoke of this bracket extends outward through the segmental aperture 30 formed in the motor case. Upon the outer arm of the switch bracket is secured the cam switch plate 31, which is preferably in the form of slightly dished or laterally beveled disk having its convex side presented outward, which disk is extended upward so as to be substantially co-axial with the pintle 26 which carries the controlling arm and the switch bracket.

The Y-shaped peripheral notch 32 is provided in the upper half of the switch plate, 95 and upon the inner side of the handle arm 2^a is secured the laterally yielding spring 33, upon which is located the detent 34, which is adapted to operate in the Y-notch to throw the switch for opening and closing the circuit.

When the circuit is closed, the parts are in the position shown in full lines in Figs. 2, 4 and 6, with the handle arm inclined rearwardly, and when the handle arm is swung forward to upright position, it is evident that the detent 34 will pass freely over the rear edge 35 and will strike the forward edge 35^a of the notch 32 in the switch plate, thus rotating the plate clockwise, as viewed in Figs. 2 and 4, and swinging the switch bracket 28 for opening the circuit, as shown in broken lines in Figs. 4 and 6; after which the detent 34 passes freely over the forward edge 35 of the switch plate, and is in position for being swung rearward by the handle arm to reverse the operation for closing the circuit.

In these operations it will be understood that the controlling arm 25 is held in one 120 position by the expansion spring 29 connecting its free end with the yoke of the switch bracket, until the swinging of the bracket has carried the spring to and beyond the axis of the switch arm whereupon the action of the spring carries the controlling arm suddenly to its other position.

In event the switch plate has been operated by means other than the detent 34 on the handle arm, and the notch is not 130

positioned to receive the detent peripherally, it is evident that the convexity of the outer side of the plate serves to deflect the detent outwardly as shown by dotted lines in Fig.

5 3, by a yielding of the spring plate 33, so as to pass the solid portion of the plate and permit the detent to enter the Y-notch from the side of the plate, whereupon it is in normal position to operate the switch as

10 before described.

In the normal relation of the parts as described, when the circuit is closed and the machine is operating with the handle inclined rearward, the switch will be automatically operated to open the circuit by merely swinging the handle forward into the upright position shown in Fig. 1; and the switch will again be automatically op-

erated to close the circuit, by merely swinging the handle rearward from an upright 20 position to the inclined position shown in Fig. 2.

I claim:

A vacuum cleaner having a swinging propeller handle arm thereon and an electric 25 switch therein, a rotatable plate operatively connected with the switch having a notch in its periphery, and a laterally yielding spring detent on the arm normally operating into and out of the notch for alternately 30 operating the plate in opposite directions, the face of the plate being beveled for deflecting the detent to enter the notch from the side of the plate when the same is abnormally positioned.

GEORGE R. PAULUS.
